UNITED STATES PATENT OFFICE.

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

GAS-ENGINE.

1,279,774.

Specification of Letters Patent. Patented Sept. 24, 1918.

Application filed September 22, 1906, Serial No. 335,833. Renewed February 3, 1917. Serial No. 146,831.

To all whom it may concern:

Be it known that I, CARL G. SPRADO, a citizen of the United States, residing at Milwaukee, in the county of Milwaukee and 5 State of Wisconsin, have invented certain new and useful Improvements in Gas-Engines, of which the following is a specification.

This invention relates to gas engines of 10 the explosion type and its purpose is to increase the efficiency and economy of such engines by providing perfect regulation at each and any of the various loads within the capacity of the engine.

15 This invention provides for the use of a constant explosive mixture, for a given load, that is, for that load, the proportions of air and gas which compose said mixture remain constant, though there is a means capable of 20 being adjusted according to the quality of the gas, but do vary with variations in the loads upon the engine. By keeping the proportions of air and gas composing the explosive mixture constant for a given load uniformity is secured in always attaining the 25 maximum explosive effect especially as this invention also provides for a constant compression or density of the explosive mixture at the moment of ignition.

30 While using a constant explosive mixture for a given load and exploding it at a constant compression the volume of explosive mixture exploded at the several explosions may be varied within very wide limits, these 35 limits being the volume of the explosion chamber or cylinder and zero, the volume exploded being proportional to the load upon the engine, the greater the load the greater the charge of the explosive mixture 40 required, and the smaller the load the smaller the explosive charge required.

This invention includes the regulation of gas engines in the manner just explained and apparatus for effecting such regulation.

45 It is also well known that the explosive effect of any mixture varies according to the density of the mixture at the moment of explosion.

50 As the volume of the explosion chamber or cylinder of a gas engine is constant, and according to this invention variable quantities of the explosive mixture may be intro-

duced into said explosion chamber or cylinder, and it is advisable to keep the density of such variable quantities constant at the 55 moment of ignition, it is necessary to use an inert filling or displacing medium in the cylinder which is introduced into the cylinder at a density and pressure dependent upon the density and pressure of the explosive mixture at the time when it is admitted into the cylinder. 60

Under ordinary conditions air at atmospheric pressure is mixed with gas at practically the same pressure for forming the 65 explosive mixture, and under such conditions it is preferred to use air at atmospheric pressure for the filling or displacing medium.

If the explosive mixture be admitted at 70 any other pressure than atmospheric, the filling or displacing medium may be and ordinarily should be supplied at a corresponding pressure. Instead of using air as the filling or displacing medium some other suitable medium may be employed and such medium may be inert, as for example, spent furnace gases and in some localities where it can readily be obtained carbon dioxide. 75

When the load upon the engine is such 80 that the filling or displacing medium is introduced into the explosion chamber or cylinder of the engine, in addition to the proper charge of explosive mixture, this invention provides a stratification of the 85 charge in the midst of the filling or displacing medium. In other words, on the so-called "suction stroke" of the engine the filling or displacing medium flows into the cylinder behind the piston as the piston re- 90 cedes and at the proper point of the stroke, as determined by the load and indicated by the position of the governor, the explosive mixture flows in behind said medium for the required part of the stroke as determined by the load and indicated by the position of 95 the governor, the charge of explosive mixture being in turn followed by the filling medium for the remainder of the "suction stroke."

100 Thus the cylinder at the beginning of the compression stroke is always filled with gases at the same pressure no matter how large or how small the charge of explosive mixture may be.

This "sandwiching" of the charge of explosive mixture results in several advantages. The filling medium fills the ports and so confines the explosion within the cylinder. In large engines which are usually thoroughly water jacketed, the minimum surface of the charge is exposed to a cooling influence. The charge of explosive mixture at the time of its explosion raises the temperature and pressure of the filling medium uniformly and thus stores as it were a part of its energy in the filling medium, which energy is gradually expended as in the ordinary hot air engine, the engine at all times indicating by the governor and supplying the size of charge of explosive mixture required to maintain a constant speed no matter how conditions vary.

For carrying out this invention the following described apparatus may be employed but the broad features of this invention are not limited to the structural features shown.

In the drawings which form a part of this specification and on which the same reference characters designate the same elements in each of the several figures,—

Figure 1 is an elevation of a gas engine embodying this invention.

Fig. 2 is a sectional elevation taken on the line *a*—*a* of Fig. 1 looking in the direction indicated by the arrow, parts that would appear in the rear of said figure being omitted for the purpose of clearness of illustration.

Fig. 3 is a sectional elevation of the valve operating mechanism taken on the line *b*—*b* of Fig. 2.

Figs. 4, 5, 6 and 7 are diagrammatic illustrations of the desired stratification of the air charges and the charge of explosive mixture in the cylinder.

Fig. 8 is a plan view of a detail.

Referring to Fig. 1, the reference character 1 indicates the foundation for the cylinder 2 and frame 3 of the engine; 4, the main shaft; 5, the crank arm; 6, the connecting rod; 7, piston rod; all of which may be of any ordinary or preferred type.

On the main shaft 4 is a bevel wheel 8 meshing with the bevel wheel 9 of twice its size, which is secured to the shaft 10, from which shaft motion is transmitted to the valve gears and the governor 11.

The engine shown is a double acting engine of the four-cycle type and consists of the single cylinder 2 at each end of which are disposed inlet and exhaust valves, the inlet valves being designated by 100 and 200 and the exhaust valves by 300 and 400, respectively.

Referring to Fig. 2, the admission valve mechanism comprises a casting 101 provided with a gas port 102 and a separate air port 103. 104 designates the admission valve

which controls the entrance of air alone or a mixture of air and gas to the cylinder, as the case may be. 105 represents the gas valve; 106 a stuffing box mechanism which is adapted to be removed bodily so that the gas valve 105 may be removed if necessary. The stem 70 of the valve 104 is provided with a collar 108 between which and the stuffing box is compressed a spiral spring 107 to hold the valve 104 to its seat. 109 represents a partition in the casting 101 by which the stem of the valve 104 is guided. 110 represents a rocking lever resting upon said valve stem and pivoted to the casting; and 111 represents a rocking arm also pivoted to the casting and adapted to be rocked upon the lever 110 to move the valve 104 from its seat. The arm 111 is rocked by the rod 112 secured to the eccentric 113 which in turn is secured to the shaft 10.

Referring to Fig. 3, reference character 85 105 indicates the gas valve to which are secured rods 118 extending through stuffing boxes in the casting and which are made of separable parts united by couplings 120. Helical springs 119 encircle these rods 118 90 and bear against the couplings 120 at one end and against projections on the casting, through which the rods pass, at their other ends, the object of the springs being to return the gas valve to its seat. These rods 95 118 are secured to a member 117 which slidably engages with the guide 116 and to the member 117 is pivoted the rocker 115 which is connected with the rocking arm 111 and rod 112 by the link 114. The driving linkage as described it will be seen constitutes a permanently positively connected linkage as contradistinguished from a tripping gear or a rotating cam tappet driving gear. This rocker 115 is adapted to rock upon the middle arm of a three-armed lever 16, which is pivoted to the casting 101 and is connected by means of the rod 15, crank 171, shaft 170, crank 14, link 13 and lever 12, with the governor 11. The three-armed lever 16 has its two outer arms pivoted to the casting in a line coinciding with the line of the pivot of the rocker 115 in the member 117 when the member 117 is in its lowest position, or in other words, when the gas valve 105 is upon its seat. 110

The middle arm of the three-armed lever 16 is dropped out of the plane of such pivots so that it will lie directly under the rocker 115 and be in contact with it. The purpose of this construction is to avoid noise by keeping these parts always in contact and providing only for a rocking of one member upon the other. 115

Reference character 301 indicates the exhaust valve; 302, the passage for the exhaust gases which may lead to any convenient exit; 303 represents the stuffing box 125

for the stem of said valve; 304, a spiral spring which acting in conjunction with a collar 306 secured to its stem and the housing 305 retains the valve upon its seat. 307 5 represents a lever pivoted to the valve casing and resting against the stem of the valve 301; and 308 represents a rocking lever also pivoted to the valve casing and rocked by the connecting rod 309 which is secured to the eccentric 310, said eccentric being secured to the shaft 10. 10 130 represents flanged projections which are made integral with the valve casings; 140 represents a conduit secured to said projections and provided with a gas passage 141 and air passage 142. 150 represents the gas main which communicates with said gas passage; and 151 represents an air port through which air is admitted to said air 20 passage, the proper proportions of air and gas being adjusted for quality of gas by valves and the adjusting mechanism 152 which consists of an operating handle and intermeshing gears upon the shafts of the 25 respective valves, the latter not being shown.

Reference character 500 represents sparking plugs or igniters by which the ignition of the explosive mixture is secured.

The operation of the engine is as follows:

30 The engine being in motion, the shaft 4 is revolving, causing the shaft 10 to revolve and the eccentrics secured thereto which cause the opening of the inlet valve 104 and the exhaust valve 301 at the proper intervals by means of the mechanism shown, which being a common form of valve operating mechanism, the action will be readily understood.

At the same time that the rocking arm 111 40 is being operated, and simultaneously and in conjunction therewith, the rocker 115 is operated. This latter rocker rocking upon the middle arm of the three-armed lever 16 affects the gas valve according to the inclination of the three-armed lever 16 as influenced by the governor 11. For example, if the engine be considered as working under a normal load with the valve mechanism in the position shown by Fig. 2, an increase 45 of load and consequent decrease of speed of the engine would result in lowering the arm 12, raising the connecting rod 15, tilting the outer end of the member 16 upward so that the rocking arm would open the gas valve 50 sooner and keep it open for a longer period and at the same time give the valve an increased lift, thus increasing the amount of mixture as well as the proportion of gas in the mixture.

60 If, on the contrary, the load on the engine were to decrease with a consequent increase of speed of the engine, the lever 12 would rise, the connecting rod 15 would lower, the outer end of the three-armed lever 16, where

it is connected to rod 15, would lower, with 65 the result that the rocker 115 would raise the gas valve later and keep it open for a less period of time, and at the same time give the valve a decreased lift, thus decreasing the amount of mixture as well as the proportion of gas in the mixture. 70

The inlet and outlet valve mechanisms at the opposite end of the cylinder are duplicates respectively of those already described at length. 75

Figs. 4, 5, 6 and 7 are diagrammatic illustrations of the theoretical stratifications existing in one end of the cylinder at the beginning of the compression stroke and at the end thereof or moment of ignition. 80 Figs. 4 and 5 represent the conditions when the load upon the engine requires a volume of the explosive mixture equal to one-half the volume of the cylinder and Figs. 6 and 7 represent the conditions when the load 85 upon the engine has fallen so low that the volume of explosive mixture required is only one-third the volume of the cylinder. By volume of the cylinder in this explanation is meant that volume inclosed between 90 the piston at its extreme limit of motion and the more remote cylinder head.

In these diagrams A represents the filling or displacing medium, air; M the explosive mixture; C the cylinder; P the piston; and 95 R the piston rod.

As shown by Figs. 5 and 7, the igniters are placed at the middle point of the compression space so they are always in position to ignite the explosive mixture without regard 100 to the volume of the charge.

What I claim is,—

1. In an explosion engine, the combination with a cylinder, of a chest having an air chamber and a gas chamber, the former 105 communicating through the main admission port with the cylinder, and the latter communicating with said air chamber through a port aligned with the admission port, a puppet valve for said main admission port having a stem extending through said aligned port, a puppet valve for said gas port sleeved upon the stem of said main valve, timed operating mechanism for the main 110 valve and an operating mechanism for the gas valve comprising a lever engaging the stem of said valve, an operating member engaging the opposite end of said lever, and a shiftable fulcrum for said lever whereby 115 the amplitude of movement imparted to said valve will be varied.

2. In an explosion engine, the combination with a cylinder, of a mixing chamber directly communicating through the main 125 admission port with said cylinder, an air supply chamber in constant communication with the mixing chamber, a gas chamber communicating with said mixing chamber

- through a port alined with the main admission port, a puppet valve controlling the main admission port and having its stem extending through the gas port, a valve sleeved upon said stem controlling said gas port, means for varying the degree of opening of said gas valve, and means for opening the main admission port valve in advance of the gas valve and for closing the gas valve in advance of the main admission port irrespective of the degree of opening of said gas valve.
3. In an explosion engine, the combination with a cylinder, of a mixing chamber communicating through the main admission port with said cylinder, a gas supply connection communicating with said mixing chamber, a valve controlling communication between said chamber and said connection, an air supply connection communicating with the mixing chamber at a point intermediate the main port and the point of communication of the gas supply with the mixing chamber, means for varying the degree of opening of said gas valve, and means for opening the main admission port valve in advance of the gas valve and for closing the gas valve in advance of the main admission port valve irrespective of the degree of opening of said gas valve, said air supply being in all positions of adjustment of the gas valve in communication with the mixing chamber upon both the opening and closing of the gas valve.
35. 4. In an explosion engine, the combination with a cylinder, of a mixing chamber communicating through the main admission port with said cylinder, a gas supply connection communicating with said mixing chamber, a valve controlling communication between said chamber and said connection, an air supply connection in constant communication with the mixing chamber at a point intermediate the main admission port and the point of communication of the gas supply with the mixing chamber, means for varying the degree of opening of said gas valve, and means for opening the main admission port valve in advance of the gas valve and for closing the gas valve in advance of the main admission port valve irrespective of the degree of opening of said gas valve, said air supply being in all positions of adjustment of the gas valve in communication with the mixing chamber upon both the opening and closing of the gas valve.
40. 5. In an explosion engine, the combination with a cylinder, of a chest having an air chamber and a gas chamber, the former communicating through the main admission port with the cylinder, and the latter communicating with said air chamber through a port alined with the admission port, a puppet valve for said main admission port having a stem extending through said alined port, a puppet valve for said gas port sleeved upon the stem of said main valve, timed operating mechanism for the main valve and an operating mechanism for the gas valve comprising a permanently positively connected linkage including two cam elements permanently in contact, and means for adjusting the position of one of said elements to change the lift of said gas valve.
45. 6. In an explosion engine, the combination with a cylinder, of a mixing chamber directly communicating through the main admission port with said cylinder, an air supply chamber in constant communication with the mixing chamber, a gas chamber communicating with said mixing chamber through a port alined with the main admission port, a puppet valve controlling the main admission port and having its stem extending through the gas port, a valve sleeved upon said stem controlling said gas port, a permanently positively connected linkage for varying the degree of opening of said gas valve, and means for opening the main admission port valve in advance of the gas valve and for closing the gas valve in advance of the main admission port irrespective of the degree of opening of said gas valve.
50. 7. In an explosion engine, the combination with a cylinder, of a mixing chamber communicating through the main admission port with said cylinder, a gas supply connection communicating with said mixing chamber, a valve controlling communication between said chamber and said connection, an air supply connection communicating with the mixing chamber at a point intermediate the main port and the point of communication of the gas supply with the mixing chamber, a permanently positively connected linkage for varying the degree of opening of said gas valve, and means for opening the main admission port valve in advance of the gas valve and for closing the gas valve in advance of the main admission port valve irrespective of the degree of opening of said gas valve, said air supply being in all positions of adjustment of the gas valve in communication with the mixing chamber upon both the opening and closing of the gas valve.
55. 8. In an explosion engine, the combination with a cylinder, of a mixing chamber communicating through the main admission port with said cylinder, a gas supply connection communicating with said mixing chamber, a valve controlling communication between said chamber and said connection, an air supply connection in constant communication with the mixing chamber at a point intermediate the main admission port and the point of communication of the gas supply with the mixing chamber, a permanently positively connected linkage for varying the degree of opening of said gas valve,

and means for opening the main admission port valve in advance of the gas valve and for closing the gas valve in advance of the main admission port irrespective of the degree of opening of said gas valve.

9. In an explosion engine, the combination of a fuel valve, and means for operating said valve comprising permanently positively connected linkage including two cam ele-

ments permanently in contact and means for adjusting the position of one of said elements to change the lift of said valve.

In testimony whereof, I affix my signature in the presence of two witnesses.
